(57) **CLAIM**

The ornamental design for a silencer, as shown and described.

DESCRIPTION

FIG. 1 is a perspective view of a silencer showing my new design;

FIG. 2 is a rear view thereof;

FIG. 3 is a front view thereof; and,

FIGS. 4-7 are a side views thereof.

The broken lines in the figures are for the purpose of illustrating environmental structure only and form no part of the claimed design.
